UNITED STATES PATENT OFFICE.

JOHN B. TIMBERLAKE, OF JACKSON, MICHIGAN, ASSIGNOR TO J. B. TIMBERLAKE & SONS,
OF JACKSON, MICHIGAN, A CORPORATION OF MICHIGAN.

DESIGN FOR AN EASEL.

No. 39,318.

Specification for Design.

Patented May 26, 1908.

Application filed February 17, 1908. Serial No. 416,434. Term of patent 14 years.

To all whom it may concern:

Be it known that I, JOHN B. TIMBERLAKE, a citizen of the United States, residing at Jackson, in the county of Jackson and State of Michigan, have invented a new, original, and ornamental Design for Easels, of which the following is a specification, reference being had to the accompanying drawing, forming part thereof.

The figure is a perspective view of an easel showing my new design.

I claim:

The ornamental design for an easel, as shown.

JOHN B. TIMBERLAKE.
